UNITED STATES PATENT OFFICE.

JAMES H. SMITH, OF WATERTOWN, MASSACHUSETTS.

OIL BURNER.

Application filed January 12, 1922. Serial No. 528,788.

To all whom it may concern:

Be it known that I, JAMES H. SMITH, a citizen of the United States, and resident of Watertown, in the county of Middlesex 5 and State of Massachusetts, have invented a new and Improved Oil Burner, of which the following is a full, clear, and exact description.

My invention relates to an oil burner, and 10 aims to provide certain new and useful improvements in connection with a device of this character, and more particularly a type of burner which is capable of utilizing kerosene, and is also adapted for household 15 purposes.

It is a well appreciated fact in connection 20 with commercial burners, that considerable difficulty has been experienced, incident to the fact that the heat of the nozzle was so intense as to result in an excessive amount of expansion, and ultimate distortion of the parts, thus destroying the further usefulness of the burner.

Various attempts have been made to overcome this difficulty but with the exception of 25 structures which are relatively complicated and proportionately expensive these attempts have for the most part, proven unsuccessful.

Thus, it is an object of my invention to 30 provide a nozzle or burner proper, capable of being utilized in connection with any type of low grade volatile fuel, but particularly adapted to consume kerosene, and by means 35 of the construction of which the parts will not be damaged while in operation, incident to the action of heat aside from the fact that by means of my improved nozzle the heat will be more evenly and extensively distributed.

A further object of this invention is the 40 construction of a device of the character stated which shall produce an extremely intense flame, and the parts of which shall be extremely simple so as to render the construction of the device possible at an extremely nominal figure, aside from the fact that the danger of imperfect operation will be reduced to a minimum.

Further objects of this invention will become apparent in the annexed specification 45 taken in connection with the drawings, which latter illustrate one practical embodiment of the same, and in which:

Figure 1 is a side elevation of my im-

proved type of burner, and showing the same associated with a conventional type of stove.

Figure 2 is a plan view of the nozzle or burner proper.

Figure 3 is an enlarged sectional side view 60 of the essential construction of the burner, and

Figure 4 is a transverse sectional view taken along the line 4—4 of Figure 1.

Referring now more particularly to Figure 1 it will be seen that the reference numeral 5 indicates the conventional pressure tank or other suitable source of fuel supply from which, by means of a pipe 6, fuel is conducted to the generator, it being understood that, as, in the embodiment illustrated a conventional type of stove 8 is positioned, it being understood also that any desirable type of control valve 7 may be utilized to regulate this flow.

Any desired type of generator may be utilized in connection with my burner but I preferably employ a generator of the type which includes a casing 9, one end of which is connected to the pipe 6, the opposite end 80 providing a discharge 10, it being noted that the interior of the casing 9 may be filled with suitable material 11 in the usual manner, and may also provide screens 12.

The vaporized gases are ejected from the discharge end 10 and bridge the gap existing between this end portion and the outer end of the elbow 13 it being noted that during this operation a sufficient quantity of air enters the elbow 13 to facilitate combustion. 90 Connected to the opposite end of the elbow is a burner proper, which in the embodiment illustrated includes a body 14 formed with a plurality of openings or slots 15. It will be seen that the body 14 is preferably annular, and concentrically disposed within this body is a second body 16, it being noted that a perforate tube 17 is interposed between these two elements for a purpose hereinafter specified.

Now with a view of retaining the whole properly assembled, I preferably utilize a stand including a body 18 formed with an extension 19, the latter supporting the generator at a point above the burner. Also 105 with a view of protecting the gap existing between the discharge end 10 of the casing 9 and the outer end of the elbow 13, I preferably positioned a plate 20 adjacent the end 110 of the generator so that the flames emanat-

ing from the burner or nozzle will not bridge to the exposed gases and ignite the same.

Thus it will be seen that the fluid fuel is 5 efficiently vaporized within the generator, subsequent to which the same passes to the burner, it being noted that during this stage of the operation, the fuel receives sufficient oxygen to induce sufficient combustion.

10 After the fuel mixture passes into the interior of the body 16 it is free to flow through the perforations of the tube 17 and so into the atmosphere, it being noted that ignition takes place at this point. Also due to the 15 peculiar construction of the burner it will be appreciated that regardless of the degree of intensity of the heat, that a ratio of expansion between the various tubes will not be such as to cause a distortion of the same, 20 as is now the case where a single member is utilized. Further, due to the mounting and disposition of the generator, it will be found that the latter is subjected to the fullest benefits of the heat produced, and 25 that a most efficient vaporization is thus accomplished.

Thus all of the objects set forth in the preamble of this specification are achieved, and it will be understood that numerous 30 modifications of structure might readily be resorted to without in the least departing from the scope of my claims; which are—

1. A burner including a pair of tubular bodies disposed one within, and spaced from,

the other, said bodies being formed with 35 openings, and a perforated member interposed between said bodies and having certain of its perforations in line with said openings.

2. A burner including a pair of bodies disposed one within, and spaced from the 40 other, said bodies being formed with openings, and a perforated tube interposed between said bodies and having certain of its perforations disposed in line with said openings. 45

3. A burner including a body formed of three substantially concentric tubular members, two of these members having registering openings, and the third member having 50 perforations opposite such openings.

4. A burner including a body formed of an outer cylindrical member, an intermediate cylindrical member inside the outer member, and an inner cylindrical member inside the intermediate member, the inner and 55 outer members having registering openings and the intermediate member being perforated opposite said openings.

5. A burner including a body formed of three substantially concentric tubular members, two of these members having registering openings, the third member having 60 perforations opposite such openings, the members interfitting snugly, and strengthening means for the burner, including ring-structures encircling the outer member near opposite ends of the burner. 65

JAMES H. SMITH.
